J. W. Allen, Waterford, N. H. Letters Patent No.
192 - dated August 10th 1848

The Schedule referred to in these Letters Patent and
making a part of the same

Dec. 692

To all whom it may concern:

Be it known that J. Frederick M. Klein of Waterford, in the County of Saratoga, and State of New York, have invented a new Design for a Radiator or air tight stove, which is described as follows, reference being had to the annexed drawings of the same marking part of this specification.

Figure 1 is a front view of the Radiator or stove.

Figure 2 is a drawing of the top plate.

Figure 3 is a plan of the bottom plate.

The front plate of this stove is cast with a foliated base resting upon ornamented legs having needed projections at the angles, crowned by an enriched foliated entablature, having the space between the angular projections, entablature, and base panneled and ornamented with various characters of figures & flowers and a circular ornamented register as represented in the front elevation fig. 1.

The bottom plate is cast with a flowered border sunken panneled and enriched edgings as represented in figure 3.

The top plate is cast with flowered edging, heads in bas relief, and raised panneled, ornamented around the edges as represented in figure 2.

The end plates are ornamented with the same character of ornaments as the front, and panneled in like manner, forming a composition when taken as a whole which is entirely new.

What I claim as my invention and desire to secure by Letters Patent is the above described design for an air tight stove, which is fully set forth in the drawings accompanying the description.
